(57) **CLAIM**

The ornamental design for a toilet paper roll holder, as shown and described.

DESCRIPTION

FIG. 1 is a perspective view of a toilet paper roll holder showing my new design;

FIG. 2 is a front elevational view of the toilet paper roll holder seen in FIG. 1;

FIG. 3 is a rear elevational view of the toilet paper roll holder seen in FIG. 1;

FIG. 4 is a right side elevational view of the toilet paper roll holder seen in FIG. 1, the left side elevational view being a mirror image thereof;

FIG. 5 is a top plan view of the toilet paper roll holder seen in FIG. 1; and,

FIG. 6 is a bottom plan view of the toilet paper roll holder seen in FIG. 1.

In the drawings, the broken lines depict portions of the toilet paper roll holder that form no part of the claimed design. Shade lines, having a combination of long and short lines in the drawings, show contour and not surface ornamentation.
